UNITED STATES PATENT OFFICE.

ROLANDES WHITAKER, OF BIGELOW, ARKANSAS.

BAND-SAW GUIDE.

981,340.

Specification of Letters Patent. Patented Jan. 10, 1911.

Application filed September 19, 1910. Serial No. 582,663.

To all whom it may concern:

Be it known that I, ROLANDES WHITAKER, a citizen of the United States, residing in Bigelow, in the county of Perry and State of Arkansas, have invented certain new and useful Improvements in Band-Saw Guides, of which the following is a specification.

My invention relates to guides for band saws of the class in which provision is made for adjusting the different members of the guide to accommodate saws of different widths, the object of my invention is to provide a guide of this class which may be readily applied to different kinds of sawing machines, which is simple in construction, is composed of relatively few parts, is readily adjusted and when once set is firm and rigid and performs its functions with accuracy.

20 In carrying out my invention, I provide a base plate which is adapted to be attached to the bed plate of a sawing machine, and which carries the two stationary members of the guide. On this base plate I provide an adjustable section, carrying the other two guide members which are adapted to be moved toward and from the stationary members to accommodate saws of different widths. The adjustable section slides on parallel rails formed on the base plate and is connected thereto by bolts which when loosened permit it to be adjusted but which, when tightened, provide a firm and rigid connection between the sliding section and the base. Each guide member comprises a housing, carrying an adjustable guide block, provided with a facing of suitable material such as Babbitt metal.

25

In the accompanying drawings:—Figure 1 is a top plan view of a band saw guide embodying my improvements. Fig. 2 shows a side elevation thereof, indicating its relation with the saw to which it is applied, the base plates of the sawing machine being indicated by dotted lines. Fig. 3 shows a vertical central section on the line 3—3 of Fig. 1. Fig. 4 shows a cross section on the line 4—4 of Fig. 1. Fig. 5 is a detail view, showing particularly the manner of arranging a counter-sunk plate in the guide housing. Fig. 6 shows a section on the line 6—6 of Fig. 5.

50 The base plate, A, comprises two parallel arms, α , α , having a long narrow space, α' , between them to receive the saw and connected at one end by a solid portion, α^2 .

Bolt holes, α^3 , α^4 , α^5 , are formed in the solid portion, α^2 , and in the arms near their outer ends as shown in Fig. 1. Longitudinally arranged parallel rails, B, B, are formed on the arms of the bifurcated bed plate and on a part of the solid portion, α^2 thereof.

Formed integrally with or rigidly secured to the arms of the bifurcated bed plate near their outer ends are the housings, C, of the stationary guide members. Each housing is formed with a chamber to receive a guide block, D, carrying a wearing plate, d, of Babbitt metal or other suitable material and each housing is provided with a plate E, 70 countersunk in a recess in the housing in the manner illustrated in Figs. 5 and 6. The plates, E, receive the end thrusts of the set screws, F. When the set screws are loosened, the pressure of the plates E, on the guide blocks is relieved and they may be adjusted, but when the screws are tightened the guide blocks are held firmly in their adjusted positions.

The movable section, G, comprises two arms, g , g connected at g' , by a U-shaped bend. These arms have a space between them to receive the saw and they are formed on their under sides with grooves which receive the rails, B. The arms are slotted, as indicated at H, and through these slots extend bolts, I, attached to the bed plate on opposite sides of the space, α' , and these bolts extend up through the arms of the sliding section, their upper ends being provided with nuts, h, and washers, h'. Each arm, g , carries a housing, J, for a guide block, K, provided with a wearing plate, k, and each housing has a counter-sunk plate, L, which bears against the guide block. Set screws, M and N, engage the plate, L, and when the set screws are tightened the guide block is held firmly in position. The bolts and nuts, I, h, hold the sliding section firmly on the bed plate, but by loosening the nuts the section G may 100 be adjusted on the rails, B, to vary the distance between the stationary guide blocks and the movable ones to accommodate saws of different widths.

It will thus be seen that the construction 105 is such that the guide may be readily applied to different kinds of band sawing machines and can be easily adjusted to saws of different widths and when once set is firm and rigid and will operate efficiently.

I claim as my invention:—

1. A band saw guide, comprising a base

- plate composed of two parallel arms, connected together at one end and having a space between them to accommodate the saw, guide members on opposite sides of the saw space rigidly connected with the base plate, an adjustable bifurcated section slidably mounted on the base plate and provided with guides for the saw on opposite sides of the saw space, and means for rigidly connecting the adjustable section with the base plate whereby the stationary guides and the guides on the adjustable sliding section may be arranged at different distances apart to accommodate saws of different widths.
- 15 2. A band saw guide, comprising a base plate composed of two parallel arms with a space between them to accommodate the saw, parallel rails on these arms, guide members rigidly connected with the arms, an adjustable section comprising parallel arms, grooved to fit the rails, guide members carried by these arms, and means for securing the adjustable section to the base plate.
- 20 3. A band saw guide, comprising a bifurcated base plate, guide blocks connected therewith, parallel rails formed on the base plate, a bifurcated adjustable section hav-

ing grooves fitting the rails, guide blocks carried by the adjustable section, and means for securing this section to the base plate.

4. A band saw guide, comprising a bifurcated base plate, housings rigidly connected therewith, guide blocks adjustable in the housings, a bifurcated section, housings carried thereby, guide blocks adjustable in the housings, and means for adjustably connecting the said adjustable section with the base plate.

5. A band saw guide, comprising a bifurcated base plate formed with parallel rails, guide blocks carried by the base plate, a bifurcated adjustable section having grooves fitting the rails and provided with slots running parallel with the rails, guide blocks carried by the adjustable section, and bolts secured to the base plate and extending through said slots.

In testimony whereof, I have hereunto subscribed my name.

ROLANDES WHITAKER.
